UNITED STATES PATENT OFFICE.

MINFORD S. CLARK, OF NEW YORK, N. Y.

DESIGN FOR A CARD RECEIVER AND STAND.

SPECIFICATION forming part of Design No. 16,405, dated December 8, 1885.

Application filed October 16, 1885. Serial No. 180,107. Term of patent 14 years.

To all whom it may concern:

Be it known that I, MINFORD S. CLARK, of the city, county, and State of New York, have invented a new and original Design for Card Receivers and Stands, of which the following is a full, clear, and exact description, reference being had to the accompanying drawing, making part of this specification.

The design relates to a card receiver and stand; and it consists of a stand of stacked muskets and a card-plate in the form of a drum-head at the points of the bayonets of the muskets. At the base is a tray with a pyramid of balls and rods extending to the butts of the muskets. A cannon-ball is also located 15 above the point of interlocking of the bayonets.

The nature of my design is fully shown in the accompanying perspective drawing of my 20 card receiver and stand.

A in the drawing represents a stand which is formed of a stack of three muskets that interlock at their bayonets. At the center of the base of the stand A is a pyramid, a, of 25 cannon-balls on a tray, b, from which latter extend rods b' to the butts of the muskets. A cannon-ball, d, is placed between the bayonets,

above their point of connection. At the points of the bayonets is a card-plate, D, which is made in the shape of a drum-head and ornamented in any suitable design. 30

Having thus described my design, I claim as new and desire to secure by Letters Patent—

1. The design for a card receiver and stand, composed of a stack of muskets interlocked at 35 their bayonets, a pyramid of cannon-balls on a tray at the base of the stand, and a card-receiver in the shape of a drum-head at the points of the bayonets, as shown and described.

2. The design for a card receiver and stand, 40 composed of a stack of muskets interlocked at their bayonets, a pyramid of cannon-balls in a tray at the base of the stand, a cannon-ball above the point of connection of the bayonets, and a card-plate in the shape of a drum-head 45 at the points of the bayonets, as shown and described.

In testimony that I claim the foregoing as my invention I have signed it this 19th day of September, 1885.

MINFORD S. CLARK.
